UNITED STATES PATENT OFFICE.

EDWIN NORTON AND JOHN G. HODGSON, OF CHICAGO, ILLINOIS, ASSIGNORS
TO SAID NORTON AND OLIVER W. NORTON, OF SAME PLACE.

CAN ENDING AND SEAMING MACHINE.

SPECIFICATION forming part of Letters Patent No. 294,065, dated February 26, 1884.

Application filed June 8, 1883. (No model.)

To all whom it may concern:

Be it known that we, EDWIN NORTON and JOHN G. HODGSON, citizens of the United States, residing in Chicago, in the county of Cook and State of Illinois, have invented a new and useful Improvement in Can Ending and Seaming Machines, of which the following is a specification,

The object of the present invention is to provide an automatic machine for applying the heads or ends to sheet-metal cans and seaming the same.

The invention consists, in connection with suitable molds or devices for clamping and holding the can-bodies while the heads are being applied and seamed thereon, of mechanism for feeding the can-bodies to the clamping device, suitable pistons or devices for forcing the can-heads upon the can-body, mechanism for feeding the can-heads, mechanism for seaming the can-heads to the can-bodies, and mechanism for discharging or delivering the cans from the machine.

In the accompanying drawings, which form a part of this specification, we have shown a machine embodying our invention, which is particularly adapted to unite the can-heads to the can-bodies by a form of seam commonly known as an exterior "squeezed" or "crimped" seam or joint, the same being a form of seam very much employed in square, rectangular, or pyramidal cans used for packing cooked meats and other articles. This form of seam, when properly made, practically prevents the contents of the can from coming in contact with the solder in the seam, for the reason that the parts or flanges of the seam are tightly squeezed together and the solder applied from the outside of the can.

As will be understood from the drawings, the mold or clamp in which the can-bodies are held is made in two parts or halves, one part being secured to a reciprocating piston or plunger, and the other part (or a series of them) being mounted on the periphery of a revolving wheel. This wheel is revolved intermittently, so as to bring the part-molds on its periphery successively in front of the part-mold on the piston, when the forward movement of the latter clamps the can-body securely

in the mold while the heads are being applied thereto and the seams formed. The can-bodies are automatically delivered into the part-molds on the wheel from a suitable delivery chute or mechanism, and retained and carried in said molds into position in front of the reciprocating half-mold as the wheel revolves. The can heads or ends are fed into the machine by suitable chutes or devices, and delivered in front of the mold, one at each end of the can-body. The can-heads are applied and forced on the can-body, while it is held in the mold, by reciprocating pistons or devices. The periphery of the piston-head conforming to the interior of the countersunk can head or end constitutes the mandrel or support against which the exterior crimping-jaws or seaming devices act in squeezing the flanges or parts of the seam closely together, or otherwise forming or partially forming the seam. The squeezing or crimping jaws are mounted on a slide or frame which is reciprocated either with or independently of the can-head-applying piston. The purpose of reciprocating the squeezing-jaws or seam-forming devices is to bring them in position over or around the projecting end or flange of the can-body, so that they may be closed together upon the can-head and form the seam. It is then of course necessary to retract them with the piston-applying head, in order that the mold-wheel may again revolve and bring another part-mold in position. It will be observed that the end or flange of the can-body which is united or seamed with the flange of the can-head projects out of the mold, the mold being shorter than the can-body. The crimping-jaws or seam-forming devices may be closed together or operated by cams or mechanisms similar to those employed to operate the reciprocating part-mold. By giving the squeezing-jaws and the periphery of the piston-head bevel-faces, the squeezed seam may be turned out at any desired angle to the body of the can. It will be noticed that the act of bending the seam out at an angle somewhat diminishes the length or height of the can-body, and this fact has occasioned considerable difficulty and irregularity in the operation of the machines or devices heretofore commonly em- 100

ployed to form these squeezed external seams, as in such devices the can-body was held in position while being operated upon by the jaws by simply placing it between two parallel end plates or disks. It is obvious that, if these end plates were adjusted to fit the length of the can-body and properly hold it while the first head was being applied, and the seam formed and turned out, when the operator came to apply the other head, the plates would be too far apart to properly fit the thus shortened can-body, and for this reason the device would be caused to do defective work. This difficulty, however, is obviated in some factories by employing one machine to apply the first head to the can-body and another machine, differently adjusted, to apply the other head; but this of course necessitates increased labor and more handling of the cans. By our invention or machine the can-bodies are clamped and held at their middle portion in a mold, so that both heads may be applied and seamed simultaneously, and so that the diminished length of the can-body caused by turning the seams at an angle in no way effects the operation of the machine in applying or seaming either of the heads.

In the drawings, Figure 1 is a plan view of the machine. Figs. 2 and 3 are sections on lines 2 2 and 3 3, respectively, of Fig. 1. Fig. 4 is a detail sectional view similar to Fig. 3, showing the squeezing-jaws open. Fig. 5 is a cross-section on line 5 5 of Fig. 1. Figs. 6, 7, and 8 are detail sectional views, showing the different positions of the crimping-jaws and piston in successive stages of the operation of applying the can-head and forming the seam. Fig. 9 is a view similar to Fig. 8, except that the crimping-jaws and pistons have bevel faces, so as to turn the seam out at an angle.

Similar letters of reference indicate like parts wherever used in the drawings.

A represents the frame of the machine. B is a wheel, provided with half or part molds b on its periphery, into which the can-bodies are received from a delivery-chute, C, one by one, as the wheel revolves. The periphery a of the wheel between the part-molds b serves to support the can-bodies in the delivery-chute until one of the molds or pockets comes under the chute, when a can-body drops therein. As the wheel revolves, the can-bodies are carried in these part-molds in front of a reciprocating or moving part-mold, b', the same being retained in the part-molds b by means of a curved guard, B', which extends from near the delivery-chute down in front of the reciprocating half-mold in a slot therein. Curved guides B² on each side of the wheel serve to center or adjust the can-bodies longitudinally in the mold b. The wheel B is driven intermittently, and is stopped and held stationary when each of the part-molds is brought in front of the reciprocating part-mold, while the latter is moved forward to clamp the can-body and hold it firmly while the can-heads are

being applied and seamed upon the body. The half-mold b' is secured to a two-part cross-head, D, which slides back and forth in suitable gibs, D', secured to the frame of the machine, and which is operated by cams D². The can-heads are fed to the machine by chutes E E—one on each side of the wheel—which deliver the same at each end of the can-body clamped in the mold and in front of reciprocating piston-heads G and G', by which they are forced upon or applied to the can-body.

The crimping-jaws are mounted on a reciprocating block or frame, H, which slides back and forth in suitable gibs, H', secured to the frame of the machine. The block H is reciprocated by means of a grooved cam-wheel, h, operating upon the wrist-pin or roller h', secured to the block H. The mold b b' is shorter than the can-body b², so that the ends of the can-body will project out beyond the mold a sufficient distance to leave room or stock for the seam. The can-head b³ is countersunk, so as to fit inside the can-body, and is provided with an overlapping flange, b⁴, which is bent or formed into a seam, with the can-body on the flange thereon. The crimping-jaws F F' F² F³ are mounted on the reciprocating block H, so as to enable them to be moved into position over the end of the can-body to crimp and form the seam, and to be afterward retracted, so that the wheel may revolve. The crimping-jaws F F' F² F³ are each mounted in suitable ways or gibs, I, secured to the reciprocating block H. These crimping-jaws are closed together or operated back and forth in their guides or ways by means of cams K and K' on the shaft K², which reciprocate the two-part cross-head K', to which the crimping-jaw F is secured. The jaws F² and F³ are operated from the jaw F by means of slides L, which are provided with cams or slots l, in which engage pins l', fixed in the jaws F' and F³, the slides L being connected to the jaws F by means of an arm, l², secured to the jaw F. The arm l² is secured at each end to the slides L by adjusting-screws l³, so that the slides may be accurately adjusted to give the proper movement to the jaws F' and F³. The jaw F² is operated by means of a bent lever, l⁴, which is pivoted to a bracket on the block H, and provided with a cam or slot, l⁵, which engages with a pin, l⁶, fixed in the jaw F². The other arm of the lever is connected to the slide L by means of a rod, l⁷, which should be provided with a turn-buckle for adjusting the movement of the jaw F². L' represents the gibs in which the slides L reciprocate. In this way all the crimping-jaws are simultaneously operated. The piston-heads G and G' are secured to suitable sliding heads, g, which reciprocate in gibs g', secured on the sliding block or frame H. These sliding heads g are actuated by means of the crank-wheel g², and the crank-arm g³, and slotted links g⁴ and g⁵, which are connected to the head g by means of a pin or bolt, g⁶. The pin

K^4 , which connects the cross-head K^3 with the crimping-jaw F , is made long enough to permit of the reciprocating motion of the frame H , on which the jaw F is mounted.

5 Any ordinary mechanism for intermittently revolving the wheel B may be employed—as, for example, a rock-shaft, n , and ratchet mechanism on the shaft of the wheel B , which should also be provided with a stop or check wheel 10 for holding the same rigidly in position while the can-head is being applied.

Suitable devices for intermittently operating the wheel B , the pistons G and G' , and the reciprocating half-mold we have fully shown 15 and described in Letters Patent No. 274,363, dated March 20, 1883, heretofore granted to us for improvement in can-ending machine, and as such operating mechanism does not constitute the novel features of the present invention we have not deemed it necessary to herein again describe the same at large. For 20 a more full description of these parts we make reference to said Patent No. 274,363.

Instead of the movable jaws herein shown 25 for squeezing the parts of the seam firmly together, the squeezing or seam-forming mechanism may consist of fixed or rigid jaws, in which case they should be made integral with the part-molds b and b' , and the piston-heads 30 G G' should be provided with a shoulder projecting over the flange of the can-head, as shown in Fig. 9, the forward movements of the piston-heads in that case serving not only to apply or force the can-head upon the can-body, but also to press or squeeze the parts 35 of the seam together and to turn the seam out at an angle to the can-body.

The can-head-delivery chutes E and E' are mounted on the reciprocating blocks or carriages H . When the piston-heads G G' make 40 their forward stroke to apply the can-heads to the can-body, they support the can-heads in the chutes E and E' . When the pistons are retracted, the can-heads drop down in 45 front of the pistons, so that they are fed automatically to the machine.

P represents the discharge-chute, into which the headed and seamed cans fall from the wheel B as it revolves.

50 We claim—

1. The combination, with a reciprocating part-mold and an intermittently-revolving wheel provided with part-molds on its periphery for clamping the can-body, of mechanism 55 for bending and compressing into a seam the flanges uniting the head to the body, substantially as specified.

2. The combination, with a reciprocating part-mold and an intermittently-revolving 60 wheel provided with part-molds on its periphery for clamping the can-body, of mechanism for applying the can-head to the can-body and mechanism for bending and compressing into a seam the flanges uniting the 65 head to the body, substantially as specified.

3. The combination, with a reciprocating

part-mold and an intermittently-revolving wheel provided with part-molds on its periphery for clamping the can-body, of a chute or device for delivering the can-bodies to the machine 70 automatically, chutes or devices for automatically delivering the can-heads at the mouth of the mold, pistons or devices for forcing the can-heads on the can-body, and mechanism for bending and compressing into a 75 seam the flanges uniting the head to the body, substantially as specified.

4. The combination, with the reciprocating part-mold and intermittently-revolving wheel provided with part-molds on its periphery for 80 clamping the can-body, of a reciprocating piston-head for forcing the can-head upon the can-body, and crimping-jaws projecting over the seam at the end of the can-body, and operating, in conjunction with the faces or periphery of the piston-head, to squeeze the parts 85 of the seam together, substantially as specified.

5. The combination, with a reciprocating part-mold and an intermittently-revolving wheel provided with half-molds on its periphery 90 for clamping the can-body, of a reciprocating piston-head for applying the can-heads to the can-body, and squeezing or crimping jaws mounted on a reciprocating frame or block, and operating, in conjunction with the 95 piston-head which forms the interior mandrel or support for the seam, to squeeze the parts of the seam together, substantially as specified.

6. The combination, with a device for clamping the can-body at its middle portion, of 100 mechanism for simultaneously applying or forcing both the heads upon the can-body, and mechanism for simultaneously bending and compressing into a seam the flanges uniting both the heads to the can-body, substantially 105 as specified.

7. The combination, with a mold or device for clamping the can-body, of reciprocating piston-heads for applying the heads thereto, and crimping-jaws mounted on a reciprocating block, mechanism for operating the jaws, and mechanism for reciprocating the block on 110 which said jaws are mounted, and mechanism for reciprocating the piston-heads, substantially as specified.

8. The combination, with reciprocating part-mold b' , wheel B , provided with part-molds b on its periphery, can-body delivery-chute C , curved guard B' , mechanism for revolving wheel B intermittently, mechanism for reciprocating the part-mold b' , can-head delivery-chutes E E' , piston-heads G G' , provided with peripheries or faces to fit the countersunk can-head, mechanism for reciprocating said piston-heads, reciprocating frame or block H and mechanism for operating the same, crimping-jaws F F' F'' F''' , mounted on said reciprocating block or frame, and mechanism for operating said crimping-jaws, and a chute for delivering the headed and seamed cans from the machine, 120 substantially as specified.

9. The combination, with a can-body-clamp-

ing mold or device, of a reciprocating block, seaming mechanism mounted on said reciprocating block, and a reciprocating piston-head forming the interior mandrel or support against which the seam is formed, substantially as specified.

10. The combination, with a can-body-clamping mold, of a reciprocating block, can-head delivery-chute mounted on said reciprocating block, mechanism for applying the can-head to the can-body, and mechanism for seaming the same, substantially as specified.

11. The combination, with a reciprocating part-mold and an intermittently - revolving wheel provided with part-mold on its periphery for clamping the can-body, of a reciprocating block provided with mechanism for seaming the can-head to the can-body, substantially as specified.

20 12. The combination, with a reciprocating part-mold and an intermittently - revolving wheel provided with part-molds on its periphery for clamping the can-body, of a reciprocating block, a can-head delivery-chute, mechanism for applying the can-head to the can-

body, and mechanism for seaming the same, substantially as specified.

13. The combination, with a mold or device for clamping the can-body at its middle portion, of reciprocating mechanism at each end of said mold for simultaneously seaming both heads to the can-body, and reciprocating piston-heads at each end, forming the interior mandrels or supports against which said seams are formed, substantially as specified.

35 14. The combination, with a can-body-clamping mold, of a chute or device for delivering the can-bodies thereto, a chute or device for delivering the can-heads at the mouth of said mold, mechanism for applying the can-head to the can-body, and mechanism for bending and compressing into a seam the flanges uniting the can head and body, substantially as specified.
